H. A. WINNE

ELECTRIC FURNACE CONTROL

Filed Nov. 23, 1921

Inventor:
Harry A. Winne,
by *Alfred, David*
His Attorney.

UNITED STATES PATENT OFFICE.

HARRY A. WINNE, OF SCHENECTADY, NEW YORK, ASSIGNOR TO GENERAL ELECTRIC COMPANY, A CORPORATION OF NEW YORK.

ELECTRIC-FURNACE CONTROL.

Application filed November 23, 1921. Serial No. 517,401.

To all whom it may concern:

Be it known that I, HARRY A. WINNE, a citizen of the United States, residing at Schenectady, in the county of Schenectady, 5 State of New York, have invented certain new and useful Improvements in Electric-Furnace Controls, of which the following is a specification.

My invention relates to the control of electric furnaces and has for its object the provision of means whereby an improved regulation of the furnace current is obtained in a simple and efficient manner.

My invention relates more specifically to 10 the control of an electric arc furnace in which the furnace electrodes are automatically moved in response to a variation of current in the electrode circuit. The movement of the electrode is ordinarily accomplished by an electric motor direct connected to the electrodes so as to move them up and down as required by the conditions of the circuit. Such a system is disclosed in the 15 patent to J. A. Seede, No. 1,206,603, dated November 28, 1916. The system of this patent employs a contact making ammeter for controlling the electric motor which operates the electrode. With this arrangement there is under some conditions possibility of a 20 "hunting" action of the moving member of the contact making ammeter due to lag in some of the circuit controlling parts and also due in part to momentum in the motor armature and electrodes moved thereby. One of 25 the objects of my invention is to overcome this tendency.

In carrying out my invention I provide 30 means whereby the moving member of the controlling means, such as the contact making ammeter, is supplied with a positive force tending to return it to neutral position as soon as it makes a contact which starts the motor for shifting the electrodes. This causes the member to be pulled away from 35 the stationary contact earlier in the operating cycle than would ordinarily be the case. The result is that a closer regulation of the current is obtained without the objectionable "hunting" action of the movable member. Other objects and purposes of my 40 invention will appear in the course of the following specification in which I have shown my invention embodied in concrete form for purposes of illustration.

Referring to the accompanying drawing

in which I have shown the parts more or less diagrammatically, 1 represents the receptacle of an electric furnace containing a conductive charge 2. The electrodes 3, 4 and 5 are respectively connected to supply 60 conductors 6, 7 and 8 carrying three-phase current. The motor M for operating one of the electrodes is shown connected to the electrode 5, only it is to be understood that the same arrangement may be used for each of 65 the electrodes. The connection between the motor and the electrode is through a gear 9 which has a screw threaded relation with a screw 10 connected with the electrode whereby the electrode will be moved up and 70 down very slowly through this speed reducing gear. The field of the motor F is supplied from the direct current mains 11 and 12, there being a resistance R in the field circuit controlled by a contactor 13 for 75 varying the speed of the motor. Reversing switches 14 and 15 are provided for reversing the motor armature current which is supplied from the mains 11 and 12 and a dynamic brake resistance 16 controlled by a contactor 17 connected across the motor terminals 80 is provided for quickly stopping the motor after the power is cut off. Mechanical interlocks 18 and 19 cooperate with an extension 20 on the moving element of the 85 contactor 17 for preventing the closing of one of the reversing contactors until the contactor 17, which controls the dynamic braking circuit, opens due to the substantial stopping of the motor. The two reversing 90 contactors are controlled by a contact making ammeter having an operating coil 21 connected to a current transformer 22 in the supply conductor 8, a resistance 23 being connected in parallel with the transformer 22 and winding 21 for calibrating 95 purposes. Connected with the moving core of the winding 21 is a controlling element 24 pivoted at 25 and provided with a contact 26 cooperating with the stationary contacts 27 and 28. A spring 29 tends to maintain the moving element in an intermediate position between the two contacts 26 and 27 and the dash pot 30 retards somewhat the movement of the member 24. A switch 31 100 is provided for changing from automatic control to manual control and vice versa. When the switch 31 is in position to bridge the contacts 32 the control will be automatic, whereas when it is moved over so as to en- 105 110

gage the contact 33, the control will be manual through the push buttons 34 and 35.

- As thus far described it will be seen that assuming that the switch 31 is in engagement with the contacts 32 the control of the electrode 5 will be automatically effected in accordance with the variations in the current of the supply conductor 8. If, for instance, current in the conductor 8 becomes too high the contact making ammeter will operate to make contact at 27 and energize the reversing contactor 14 whereby the electrode 5 will be raised to reduce the current. On the other hand, if the current in the conductor 8 becomes too low the contact is made at 26 so as to energize the contactor 15 and close the motor circuit in a direction to lower the electrode. Each time one of the reversing contactors opens to open the motor armature circuit the contactor 17 will close to establish a dynamic braking circuit through the resistance 16 and the other reversing contactor cannot close until the contactor 17 is opened by the slowing down of the motor substantially to rest. When the switch 31 is in the automatic position; namely, in engagement with the contacts 32, the contactor 13 will close so as to short circuit the resistance R and reduce the speed of the motor. When the switch 31 is moved into engagement with the contact 33 the control of the reversing contactors will be through the push buttons 34 and 35. In this position, however, the contactor 13 will be open and the resistance R will be in series with the field so as to speed up the motor. There will therefore be a higher speed of the motor during manual operation than during automatic operation.
- One of the principal features of my invention resides in the provision of means for setting up a force tending to move the member 24 of the contact making ammeter back toward intermediate position whenever it engages with either contact 26 or 27. As shown, this means comprises a winding 36 which is energized to move the member in either direction depending upon which of the contacts 26 or 27 is engaged. This winding 36 is energized across the direct current supply circuit 11, 12 either through resistances r or r' and one of the reversing contactors 14, 15. When contactor 14 closes due to the engagement of the arm 24 with the contact 27, a circuit is completed through the winding 36 from the supply line 11 through the resistance r , winding 36, and the upper switch arm of contactor 14 to line 12. The energization of winding 36 is now in a direction to force the arm 24 upward out of engagement with the contact 27. If the contactor 15 is closed due to the closing of the circuit at contact 26, the circuit will then be from the supply line 11 through the upper switch arm of contactor 15 through

winding 36 and to supply line 12 through resistance r' . The current through the winding 36 is now reversed so that the force upon the arm 24 is in the downward direction tending to break the contact at 26. A dash pot 37 retards the action of the winding 36 upon its moving core. It will therefore be seen that whenever the contact is made at either 26 or 27 a force is set up tending to move the arm back to the central position. The result of this is more positive action of the contact making ammeter resulting in a closer calibration with no tendency of the member to "hunt". A numerical example will make this point clear. Assuming that the member 24 balances in a neutral position with a current of one ampere in the coil 21 and that a decrease of current to .95 ampere will cause the arm 24 to make engagement with the contact 26 while an increase of current to 1.05 amperes will cause the arm to make engagement with the contact 27. Assume, now, that the current suddenly increases to 1.2 amperes, immediately the arm 24 will engage with contact 27 closing contactor 14 and causing the electric motor to raise the electrode 5. At the same time the coil 36 will be energized in a direction tending to lift the arm 24 out of engagement with the contact 27. If the force due to the winding 36 were not present, the arm 24 would not tend to separate from contact 27 until the current in the contact making ammeter had actually been reduced to 1.05 amperes and the lag of the mechanism and the overtravel of the electrode might cause the current to drop to .95 ampere before the electrode motion actually ceased. The force set up by the winding 36 may be such that the member 24 will tend to separate from the contact 27 when the current in the winding 22 has been reduced to only 1.1 amperes. Consequently, assuming the same lag and overtravel in the mechanism, at the time the electrode motion is actually stopped, the current in the coil 22 will have been reduced only to the normal value of one ampere. In other words, by the provision of my arrangement the natural tendency for an overtravel which would result in the continuous vibration or "hunting" action of the member 24 will be to a very large extent overcome.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to se-

cure by Letters Patent of the United States, is:

1. A regulating system for electric furnaces comprising in combination with an electrode, an energy supply source therefor, an electric motor for moving said electrode, electromagnetic means responsive to variations in the electrode circuit for controlling the movement of said electrode by said motor in two directions, a pair of resistance devices connected in series across said supply source, a second electromagnet mechanically connected to the first, and electrical connections between one terminal of said second electromagnet and one terminal of said motor and between the other terminal of said second electromagnet and a point between said resistance devices, whereby said second electromagnet is energized to oppose the first upon movement of said electrode in either direction.
2. A regulating system for electric furnaces comprising in combination with an electrode, an energy supply source therefor, an electric motor operatively connected to 25 adjust said electrode, reversing switches for said motor, a contact making ammeter for controlling the reversing switches having a winding in the electrode supply circuit and an element movable by said winding 30 to opposite contact making positions from an intermediate position in accordance with variations in the electrode circuit, a pair of resistances connected in series across said supply source, an electromagnet, an operating 35 connection between said electromagnet and said element, and electrical connections between one terminal of said electromagnet and one terminal of said motor and between the other terminal of said electromagnet and 40 a point between said resistances whereby said electromagnet is energized through said reversing switches concurrently with said motor to exert a force tending to return said element to its intermediate position. 45

In witness whereof, I have hereunto set my hand this 22nd day of November, 1921.

HARRY A. WINNE.
